UNITED STATES PATENT OFFICE.

ALFRED E. TITUS, OF TRENTON, NEW JERSEY.

REFRIGERATOR DOORLOCK.

Application filed October 13, 1924. Serial No. 743,827.

The object of my invention is to provide a refrigerator door lock of simple, but efficient construction which will hold the door with an air tight joint against the jamb, and 5 I provide this lock with a key controlled lock whereby the locking bolt can be firmly secured against unauthorized manipulation.

In the drawings:

Figure 1 is a front elevation of the fragmentary part of a refrigerator and its door 10 with my lock in position.

Figure 2 is a top elevation of my lock in position.

Figure 3 is a side elevation of my improved lock with one of the side plates removed and showing the locking bolt locked in its closed position.

Figure 4 is a view similar to Figure 3 with the locking bolt free to be revolved.

20 Figure 5 is a detailed sectional view of the lock housing and the parts therein.

Figure 6 is a top plan view of another embodiment of my invention.

Figure 7 is a side elevation of the same 25 with the side plate removed, the parts being in normal locked position.

Figure 8 is a view similar to Figure 7 with the parts in unlocked position.

The reference numeral 1 designates a refrigerator of improved construction having 30 a door 2 adapted, as is usual, to make an air tight joint with its jamb.

A keeper plate 3 is secured to the jamb of the refrigerator from which extends forwardly the usual keeper catch 4, said catch having a recess in its upper face into which the end of the bolt of the lock is adapted to be set. The outer edge of the keeper catch 4 is, as usual, of general cam contour over 40 which the end of the locking bolt moves in the closing of the door.

The lock comprises a housing 5, mounted on a base 6, which base has suitable screw openings whereby it is screwed to the door. 45 Said housing having a removable plate 7, which is secured by means of suitable screws passing through the openings 8, of the housing proper. The edge of the wall of the housing between the lugs carrying the screw opening 8, is recessed between said openings thereby forming a slot 9, between side plate 7 and the housing.

50 A shaft 10, is revolvably mounted in the housing 5, with its ends projecting beyond the side walls of the housing, one end (10^a) projecting materially beyond the side wall

of the housing to which end is rigidly secured an arm 11, on the other end of which is mounted a wrist pin 12. An antifriction roller 13, is mounted on the wrist pin 12, 60 which antifriction roller is adapted in the closing of the door to ride the cam like face 4, and drop into the recess of the keeper.

A helical spring is secured at one end to 65 the revoluble shaft 10, while its other end is anchored at 14, to the housing whereby the antifriction roller 13 is held, normally, in its locked position relative to the recess in the keeper, but is free to yield in riding the 70 cam surface of the keeper in the closing of the door.

A key lock is desirable on refrigerators, but with many sizes of refrigerators an efficient key lock is too expansive, therefore, I 75 have designed a simple, cheap, but effective lock for all sizes of refrigerators and this lock consists of an arm 15, which I have, for the purpose of illustrating my invention, shown as integral with the operating handle 16, which operating handle is rigidly mounted on the revoluble shaft 10 within the housing. The arm 15 is provided at its free end with a hook like formation 17, which is adapted to be engaged by the detent 18 on 80 a suitable key control lock 19 having a key slot 19'. In Figure 3, I have shown the detent 18 in engagement with the arm 15 whereby the shaft 10 is locked against movement, while in Figure 4, I have shown the 90 detent 18 out of engagement of arm 15, whereby the handle 16 and the shaft 10 are free to move in the locked or unlocking movements of the door 2.

20 is a set screw firmly securing the operating handle 16 to the shaft 10.

In Figures 6, 7 and 8 I have illustrated another embodiment of my invention in which the keeper plate 3', catch 4', housing 5', base 6', side plate 7', slot 9', arm 11' 100 with its wrist pin 12' and antifriction roller 13' are identical, in construction, with similar parts described in connection with Figures 1 to 5.

The operating handle 22 has an arm 23 105 keyed to the shaft 24 within the housing 5'. 24' is a recess in one edge of the body 23 into which the key controlled lock 25 is adapted to be moved to lock the operating handle against movement. In the hub 25' of the 110 detent is secured a suitable lock, the key hole 25^a of which is in the end of the hub.

At the bottom of the body 23 is a forwardly extending arm or lug 26 having an opening 27 therethrough to be hereinafter referred to.

28 is a bar pivotally mounted at its upper 5 end, within the housing 5' on the lug 29, said bar having a collar 30 at its upper end against which one end of the coiled spring 31 rests, the other end of said spring being seated on the lug 26, the spring, as shown, being 10 coiled around the bar 28. It will be noted that the lug 26 is slightly inclined downwardly so that when the parts are moved to the position shown in Figure 8, the upper face of the lug is at substantially right 15 angles to the bar 28. It will also be noted that the diameter of the eye 27 is greater than the diameter of the bar 28 whereby the bar is prevented from binding in said opening as the parts are moved in operation of 20 the lock.

In the claims the term "operating handle" will, unless otherwise more specifically limited, include the handle 16, 22, arm 15 and 23.

25 While I have selected the constructions shown in the drawings for the purpose of illustrating my invention, it will, of course, be understood that changes may be made therein without departing from the scope of 30 the appended claims.

What I claim is:

1. In a door lock a housing having an elongated slot in one of its walls, a bolt revolvably mounted in and extending normally

beyond the housing, an operating lever rigidly secured to said bolt in the housing and extending through said slot, an arm rigidly connected to the bolt within the housing, a key controlled detent adapted to engage said arm to lock the bolt in locked position, 40 and a spring one end of which is anchored to said bolt while its other end is anchored to the housing.

2. In a door lock the combination with a housing having side top and bottom walls, 45 an elongated slot in one of said walls, a shaft revolvably mounted in said housing with one of its ends projecting beyond the housing, an arm fixedly secured at one end to said shaft, a wrist pin on the other end of the shaft and a roller on said pin, a second arm rigidly secured on the shaft within the housing, a recess in one edge of 50 said arm, a key controlled lock adapted to operate in said recess to control the movement of the said second arm, a lug projecting forwardly from the lower end of said second arm, a bar pivotally secured at the top within the housing and extending through said lug, a coiled spring around 55 said arm, one end of which is seated on said lug, and an operating handle integral with said second arm and projecting outside the housing through said slot.

In testimony whereof I affix my signature.

ALFRED E. TITUS.
